DESIGN FOR A TRAFFIC SAFETY SIGN

Edward E. Liphard, St. Petersburg, Fla.

Application January 19, 1940, Serial No. 89,587

Term of patent 14 years

To all whom it may concern:

Be it known that I, Edward E. Liphard, a citizen of the United States, residing at St. Petersburg, in the county of Pinellas and State of Florida, have invented a new, original, and ornamental Design for a Traffic Safety Sign, of which the following is a specification, reference being had to the accompanying drawing, forming a part thereof.

In the drawing:

Figure 1 is a front elevational view of a traffic safety sign embodying my new design.

Figure 2 is a rear elevational view of the same.
Figure 3 is a side elevational view of the same.

Figure 4 is a top plan view of the same.
Figure 5 is a sectional view taken on the line 5—5 of Figure 2.

The dominant features of the design are shown in full lines in the drawing.

I claim:

The ornamental design for a traffic safety sign, as shown and described.

EDWARD E. LIPHARD.
